(57) CLAIM

I claim the ornamental design for golf practice target system, as shown and described.

DESCRIPTION

FIG. 1 is a perspective view of a golf target practice system; FIG. 2 is a front view thereof; FIG. 3 is a rear view thereof; FIG. 4 is a side view thereof; FIG. 5 is a bottom view thereof; and, FIG. 6 is a top view thereof.

The indicia and top surface apertures shown in broken lines in FIGS. 1 and/or 3 are for illustrative purposes only; and form no part of the claimed design.
